CORE DRILLING BIT

Filed Oct. 5, 1927

UNITED STATES PATENT OFFICE

RAPHAEL ROGERS CANDEE, OF MCKITTRICK, AND OSCAR FRED HARDING, OF COALINGA, CALIFORNIA

CORE-DRILLING BIT

Application filed October 5, 1927. Serial No. 224,197.

This invention relates to deep well drilling tools and more especially to a rotary, core cutting tool.

It is highly desirable in the drilling of deep wells that accurate logs be kept of the actual formation which is encountered, strata by strata. With drills not taking a core the fine cuttings mix with the circulating fluid to such an extent that only rough estimates can be made as to the probable depth of the strata from the top of the hole and of the thickness of the strata itself. This guess work of logging is very deficient where the deep strata may each be quite thin.

Various types of core taking drills have been devised and quite successfully used. With these difficulty is experienced in removing the core.

The present invention has for an object to take a core of any desired length. A further object is to provide for the ready removal of the core from the drill barrel.

Another deficiency of various forms of core drills is the inability to obtain a good specimen when the drill is running through rather soft formation which has the tendency to muck and flow down out of the drill when this is pulled out. Therefore another object is to provide means for effectively retaining a core specimen of a soft formation.

An additional object is to provide a drill constructed and designed to cut an annular swarth around a dead center zone and to form a core on the center and to provide means for by-passing the top of the core in fragments out through the side of the drill stem continuously during operation of the drill after a predetermined length of core has been cut; it being understood that the core shall be so cast off only in cases where the log of the formation is undesired.

There are other objects and advantages and features of construction and combination, and these will be made manifest in the following specification of the herewith illustrated embodiment; it being understood that modifications, variations and adaptations may be resorted to within the spirit, scope and principle of the invention as it is more directly claimed hereinafter.

Figure 1 is an axial section of the tool.

Figure 2 is a bottom plan of the bit.

Figure 3 is a side elevation of the bit.

Figure 4 is an end view of a core barrel sleeve section. 55

Figure 5 is an axial section of the assembled barrel of sleeve and cuff parts.

Figure 6 is an end view of one of the split cuffs.

Figure 7 is a plan of the core barrel head 60 centering ring.

Figure 8 is a plan of the core barrel trap.

Figure 9 is an axial section of the trap.

Figure 10 is a detail, on substantially full scale, of a fragment of the trap showing a 65 mode of mounting a trap finger.

In its illustrated form the tool includes a stout bottom piece or bit body 2 having a tapered top pin 3 for attachment to a drill collar or section 4. The bit body 2 is centrally bored and has an intermediate, annular shoulder or ledge 5. 70

On the bottom face of the bit body 2 is an inner, annular series of cutters 6 having cutting, end lips 6^a and extending inwardly 75 along the bit bore and presenting longitudinal cutting edges 6^b leaving a central core of the penetrated formation and which core stands in the bit bore as drilling proceeds.

Extending beyond the bit body 2 is a circle 80 of reaming cutters 7 having advance, bottom cutting edges 7^a which are of a length to overlap the orbit of the inner cutters 6. The cutters 7 have a substantial helical pitch on the body 2, receding from the cutting edges 7^a. 85

As the running drill goes down the core passes into a trapping means in the body 2 which is for the purpose of grappling in the core when the drill is pulled from the hole. The trap, as shown, includes a cage wall 10 90 provided with inwardly and upwardly inclined spring-leaf fingers 11 whose lower ends are riveted at 12 in openings 13 in the cage wall so that the fingers may lie back flush when the full size body of core is embraced. When the tool is pulled up the fingers spring in and take hold or if the formation is soft the fingers will flex in to form a bottom for the cage and thus retain a very material portion of the penetrated formation. 95 100

The fingers, as shown, have a helical pitch reverse from direction of rotation which is for the purpose of facilitating rotation of the cage while the fingers are engaging a hard core; the fingers having a nut-like effect advancing on the core.

The cut core passes from the bit body 2 and pin 3 up into the hollow collar 4 and this is provided with a removable core receiver or barrel forming one of the features of this invention. This barrel is made of a combination of parts constructed and arranged to greatly facilitate the extraction of the core and includes a ferrule having a base 15 seating on top of the trap wall 10 and snugly fitting the body bore so as to close off water passage at a line below a series of water holes 2^a. Above the base 15 the ferrule is reduced to a cylinder 15^a to form a space thereabout to the holes 2^a for water and is again reduced at 15^b above shoulder 15^c to snugly receive a short length of tubing or sleeve 16 of greater length than the ferrule portion 15^b.

Any desired length of barrel may be built up by abutting a number of the sleeves 16, as determined by the length of drill collar 4 or multiples thereof. The abutted sleeves 16 are detachably alined by suitable means here shown as including a line of inside sections or cuffs 17 which are of resilient metal and split at 17^a along one side. The cuffs have a diameter, when free, greater than the inside diameter of the sleeves 16 and are of equal length therewith so that joints of the assembled sleeves and cuffs are evenly broken. The cuffs 17 are contracted in diameter and then forced endwise into mounted sleeve 16 superposed in assembly on the ferrule piece. The cuff 17 form a continuous, sectional liner for the barrel sleeves 16 and receive the core as it is cut by advance of the drill.

When the tool is pulled, the sections 16—17 are successively removed from the core. To accomplish this the sections have pairs of wrench engaging holes 20, which are so disposed as to never register and therefore prevent water flow from sleeve into cuff. First, a sleeve is pulled off endwise and then the next cuff is pulled to just clear the next sleeve following which the released cuff will spring open fully loose about the enveloped core. The free cuff is then easily pulled endwise from the core. The remaining sleeves and cuffs are taken off in order in the same manner.

It will be seen that as long a core may be taken as may be desirable or practicable, since any length of core can be easily extracted from the sectional jacket, but such a capacity is not available with core drills having long one-piece barrel parts because the cores cannot be efficiently removed.

The present tool eliminates the dead cen-

ter, non-cutting zone by leaving a core on center and where it is not desired to retain the core for log record we provide means to automatically discard the core by passing it off, in small fragments, and out to one side of the drill where it is quickly abraded down by the side wall of the hole during rotation of the drill.

The discard means shown includes an upper joint 22 having a pin for the collar and a top box for attachment to the upper drill rod string (not shown). The joint 22 is chambered to form a water passage to the collar 4 and receives the upper end of the top core barrel sleeve 16. A flue or deflecting conduit 23 leads from the upper end of the core barrel and discharges at a side aperture 24. The adjacent ends of the conduit 23 and top sleeve 16 are centered and supported by suitable means here shown as a seat ring 25 having marginal water ports 25^a to permit circulation to the collar 4. The passageway in the conduit 23 pitches at an angle and therefore when the head of the core impinges on the opposed inclined face of the conduit the weight of the whole tool is effectively useful to transversely break off the core, if it is of hard stone.

The ring 25 may be of hard metal and form a fulcrum for the core when the tool acts on the head of the core to break it off for deflection into the discarding conduit 23.

If the conduit is of removable, renewable installation it can be buttressed by a backing block 27.

The invention claimed is:

1. In combination, in a drill, a bit body head having a series of helical reaming blades with straight bottom cutting edges extending under the bottom of the body and a series of bottom cutting blades; the bottom edges of both series of blades lying in a common plane.

2. In combination, in a drill, a bit body head having a series of helical reaming blades with straight bottom cutting edges extending under the bottom of the body for about one-half of the radius and which edges lie on lines tangential to the bit center and at such an angle as to sweep the cuttings inward toward the center and an inner set of bottom cutters with edges on the same bottom plane of the outer blade.

3. In combination, in a drill, a hollow center bit body having a series of helical reaming blades with straight bottom cutting edges extending under the bottom of the body and which edges lie on lines tangential to the bit center and positioned to sweep the cuttings inward, and an inner series of bottom cutting blades with straight bottom edges which lie tangential to the center and pitch in a reverse direction to the bottom edges of the reaming blades; the plane of each blade of the inner series lying at an angle of about 60° from the radial line intersecting its nose, and said

inner blades overlapping the orbit of the outer blades and all blade edges being in a common bottom plane.

4. A drilling tool including a core forming bit, a core trap cage seated therein, a drill collar detachably secured to the bit stem, a string joint removably attached to the collar, a sectional barrel having a base ferrule bearing against the said cage and having a top section seating in the said joint and whereby the barrel is clamped in place, and a string of split, self-opening core sleeves lining the barrel in broken joint relation and friction holding contact.
